Nelson W. Howard

UNITED STATES PATENT OFFICE.

NELSON B. CUTLER, OF MILWAUKEE, WISCONSIN, ASSIGNOR, BY MESNE ASSIGNMENTS, TO UNITED SHOE MACHINERY CORPORATION, OF PATERSON, NEW JERSEY, A CORPORATION OF NEW JERSEY.

WAXING AND POLISHING MACHINE.

Application filed April 3, 1922. Serial No. 549,034.

To all whom it may concern:

Be it known that I, NELSON B. CUTLER, a citizen of the United States, residing at Milwaukee, in the county of Milwaukee and State of Wisconsin, have invented certain Improvements in Waxing and Polishing Machines, of which the following description, in connection with the accompanying drawings, is a specification, like referring characters on the drawings indicating like parts in the several figures.

This invention relates to waxing and polishing machines and is herein shown as embodied in a rotary padding brush for spreading wax on heels.

After the heel of a shoe has been scoured, a thin coating of wax is usually applied by means of a heated burnishing iron. The wax is thereafter spread and worked into the surface of the heel by means of a rotary brush. As heretofore constructed such brushes have bristles of uniform length radiating from a hub. When new, the bristles are too stiff to make a good padding brush and require a long period of use to break them in. When the bristles have become sufficiently flexible they then have a tendency to spread laterally and mat down with the result that in a short time the heel comes against the hub and the wax is spread onto the upper. In padding rubber heels another defect of such brushes is that the rubber causes the bristles to pull out.

In view of these facts, an object of this invention is to provide an improved padding brush which will obviate the above disadvantages. As a feature of the invention, the illustrated brush is constructed with some long and some short bristles so that, in use, the longer bristles immediately tend to lie over the ends of the shorter ones instead of spreading laterally. As a result, a better cushioning effect is obtained from the beginning and the brush can be quickly broken in. The resulting recesses in the periphery of the brush also provide a rumble effect which gives a series of slight blows and thereby acts more efficiently in spreading the wax. With the ends of the longer bristles overlying the shorter ones, there is less tendency for them to be pulled out when used on rubber work. These and other features and advantages of the invention will

appear from a consideration of the following specification and accompanying drawings, in which—

Fig. 1 is a side elevation of the improved brush;

Fig. 2 is a front elevation;

Fig. 3 is a front elevation with a canvas or other textile covering applied to the brush; and

Fig. 4 is a side elevation with the cover partly broken away and showing the action of the bristles when a heel is being treated.

The brush comprises a hub 4 which is secured for rotation to the shaft 6 of a finishing machine. Projecting from different portions of the periphery of the hub, are clusters 8 of comparatively long relatively soft bristles, these clusters being arranged in groups. Projecting from the remaining portions of the periphery of the hub and alternating with the longer bristles are a series of clusters 10 of shorter bristles. This construction leaves a series of recesses 12 spaced about the periphery of the brush so that a rumble effect is produced in spreading the wax. It should be noted that the bristles do not extend radially from the hub but project therefrom in spiral fashion. Consequently, when a canvas cover 14 is put on the brush and drawn against its periphery by means of the usual lacing cord, all of the bristles will tend to crowd in one direction only and none of them will be crowded in a counter clockwise direction which is here shown as the direction of rotation.

In Fig. 4 a heel 16 is shown applied in working position. As the brush rotates, the leading points 18 on the longer bristles will successively contact (through the cover) with the heel and produce a slight blow. This gives a rumble effect which is more efficient in spreading the wax. The shorter bristles 10 act in the capacity of resilient supports for the longer ones. In use the longer bristles, under pressure of the work, tend to crowd towards the center and bend over the shorter bristles, being thereby prevented from spreading laterally. Although the invention has been described by reference to a specific embodiment, it should be understood that it is not necessarily limited to the illustrated construction.

Having described my invention, what I claim as new and desire to secure by Letters Patent of the United States is:

1. In a rotary padding brush for waxing and polishing the peripheries of the heels of shoes, a rotary hub, separated clusters of long flexible bristles projecting from the hub, and clusters of comparatively short bristles projecting from the hub between the first clusters and arranged to form resilient supports for the longer bristles at a point separated from the hub, the ends of said longer bristles overlying the shorter ones in use and being held against lateral spreading as they are crowded towards the center under pressure of the heels thereby preventing contact of the heels with the hub.
2. In a rotary padding brush for waxing and polishing machines, a rotary hub, clusters of comparatively long soft bristles projecting spirally from the periphery of the hub, said clusters being arranged in groups,

and clusters of shorter bristles projecting from the remaining portions of the periphery of the hub and alternating with and partially underlying the groups of longer clusters to produce a rumble effect in spreading wax, the ends of said longer bristles overlying the shorter ones and said shorter bristles acting as a resilient support for the longer ones and intermeshing with longer bristles to prevent lateral spreading.

3. In a rotary padding brush for waxing and polishing machines, a rotary hub, bristles projecting from the hub and constructed and arranged to form recesses spaced about the periphery of the brush, and resilient supports for the bristles extending from the hub and supporting said bristles near the ends thereof.

In testimony whereof I have signed my name to this specification.

NELSON B. CUTLER.
